UNITED STATES PATENT OFFICE.

WILLIAM M. RYAN, OF SHENANDOAH, IOWA.

SOLDERING-TOOL

SPECIFICATION forming part of Letters Patent No. 295,888, dated March 25, 1884.

Application filed July 30, 1883. (No model.)

To all whom it may concern:

Be it known that I, WILLIAM M. RYAN, a citizen of the United States, residing at Shenandoah, in the county of Page and State of Iowa, have invented certain new and useful Improvements in Soldering-Tools, of which the following is a specification, reference being had to the accompanying drawing and the letters and figures of reference marked thereon, in which the figure is a longitudinal central sectional view of my device.

In the said drawing, B indicates the iron, which is in outline of a similar contour to the ordinary soldering-iron head, but is recessed or hollow, as shown, and provided at its lower end with a discharge-perforation, a, and at its upper end with a filling-aperture, b. The inner walls, c, of the iron converge or incline to near the inner surface of the discharge-aperture. The iron is also provided at its upper end with a ring-extension, d, to receive the pivoted or hinged jaws of the handle, as will be hereinafter more fully explained.

C indicates the handle, which may be made of wood or other suitable material, and provided with a shank-extension, e, having its lower end terminating in an inwardly-turned abrupt hook, f. This shank-extension e is provided on its outer side near its hooked end 30 with a fulcrum-bearing, g, and a flat spring, h.

D indicates a thumb-lever, which is of T shape in outline, having one end of its cross-arm pivoted in the fulcrum-bearing g, its long arm extended upward and designed to engage the said flat spring h.

In the shoulder i of the handle C is pivoted an arm, A, which is of a construction identical, or nearly so, with that of the shank-extension. Both the shank-extension and pivoted arm are provided with a transverse perforation, k, by means of which, through the medium of a bolt and nut, the hooked ends of the

pivoted arm and shank-extension are secured to the ring end of the iron, as shown in the drawing.

N indicates a rod, which is inserted in the iron through its filling-aperture, extends down through the molten metal to the discharge-aperture to close and open the same when desired, as presently explained. The outer end of the cross-arm of the lever D is vertically perforated for the passage of the stopper-rod, and provided with a set-screw, 3, whereby the said rod may be vertically adjusted with relation to the discharge end of the iron. By this construction, it will be perceived that when the receptacle E of the iron has been filled with molten metal, and the operator grasps the handle by pressing his thumb against the upper end of the lever D the valve or stopper-rod will be drawn up out of the discharge-opening and the metal allowed to flow out, but by the operator removing his thumb from this lever the flat spring will throw the lever outward and the rod down in the discharge-opening, thus preventing the escape of any of the metal in the receptacle.

What I claim as new, and desire to secure by Letters Patent, is—

The soldering-tool described, consisting of the iron B, having the filling and discharge apertures, and provided with the receptacle E, having its inner walls converging to the discharge-aperture, and the upward loop-extension d, the handle C, having the hooked shank-extension e and shoulder i, the pivoted hooked arm A, spring h, fulcrum-bearing g, lever D, stopper-rod N, set-screw 3, and rod and nut for securing the handle to the iron, substantially as shown and described.

WM. M. RYAN.
